PERMUTATION SWITCH

Henry Haskett, Annapolis, Md.

Application April 1, 1949, Serial No. 85,009

7 Claims. (Cl. 171—97)

1

This invention relates to circuit makers and breakers and more particularly to a permutation switch by which one or more circuits may be energized upon compliance with a series of selectively predetermined conditions. The invention is particularly adapted for use with coin operated machines such as those simulating horse races or those which may be played by predicting a series of numbers but the device is in no way limited to use with these machines and may be utilized for any desired purpose for which it is adapted.

It is therefore an object of this invention to provide a permutation switch in which a series of conditions may be selected which if complied with will result in energizing one or more circuits.

It is a further object of this invention to provide a permutation switch in which one of a series of conditions may be selected which if complied with will result in energizing one or more circuits.

It is a further object of this invention to provide a permutation switch having a series of switch actuators each actuator including a plurality of switch operating elements any one of which elements may be projected into operative position by selective energization of a solenoid associated therewith.

It is a further object of this invention to provide a permutation switch in which means is provided for preventing any change in a selected condition once such selection has been made.

It is a further object of this invention to provide a permutation switch having cancellation means for cancelling a selection and returning the switch to original condition preparatory to subsequent operation thereof.

Further objects and advantages of the invention will be apparent from the following description taken in conjunction with the accompanying drawings, wherein:

Fig. 1 is a diagrammatic view showing the permutation switch of this invention and the electrical circuits associated therewith;

Fig. 2, a schematic circuit diagram for one section of the permutation switch;

Fig. 3, a fragmentary sectional view showing a switch operating element in inoperative position together with its associated solenoid and a cancellation means, the cancellation means being shown in full lines in inoperative position and in phantom in operative position; and,

Fig. 4, a view similar to Fig. 3 showing the switch operating element in operative position.

With continued reference to the drawing, there is shown in Fig. 1 a permutation switch which

2

may conveniently comprise switch actuators 10, 11 and 12 forming a three-section switch. Obviously as many sections as necessary may be incorporated in order to obtain the desired results. Switch actuators 10, 11 and 12 may be mounted for rotation on a single shaft 13 or if desired may be mounted on individual shafts. Each actuator is provided with a gear or other equivalent driving means 14 which may be driven by any desired mechanism such as various well known coin operated machines or the like and since all of the actuators are identical a description of one will suffice for all.

The actuator 10 is shown in the form of a wheel but this is not necessary to the invention since the actuator may be manufactured in any convenient or desired form. As shown, a plurality of switch operating elements 15 are mounted for sliding movement axially of the wheel 10 and these elements are preferably arranged in the form of a circle. Each element 15 comprises an elongated pin slidably mounted in the side walls 16 there being a solenoid 17 within the wheel 10 associated with each element 15 and having a coil 18. Also positioned within the wheel 10 is a disk 19 of insulating material, there being an aperture 20 in this disk for each element 15. Adjacent each aperture are a pair of contacts 21 which are engaged by a wedge-shaped member 22 mounted on each element 15 and which serves to short circuit contacts 21 when the element 15 is in inoperative or retracted position. If desired, the disk 19 and associated contacts 21 may be mounted exteriorly of the wheel 10.

In order to move the element 15 to operative or extended position it is only necessary to energize the coil 18 of the solenoid 17 and to move any of the elements 15 to inoperative position 40 there is provided a cancellation disk or plate 23 provided with an aperture 24 for each element 15, this plate being movable axially of the wheel 10, and being guided in such movement by an extension 25 slidably engaging an aperture 26 in the wheel 10. A washer or the like 27 is secured to each element 15 outwardly of the cancellation plate 23 and upon movement of the cancellation plate from the position shown in full lines in Fig. 3 to the position shown in phantom the plate will engage washer 27 and move element 15 to retracted or inoperative position.

Cancellation plate 23 may conveniently be operated by a solenoid 28 shown diagrammatically in Fig. 2.

55 In order to energize coils 18 of solenoids 17 a

series of slip rings 29 are associated with each actuator there being one of these slip rings for each solenoid. Additional slip rings are also provided for a purpose which will presently be described. A brush or the like is associated with each slip ring and those corresponding to each solenoid 17 lead to a series of contacts 30 of a selector switch 31 having an arm 32 for engaging any selected contact.

Any suitable power source may be provided and from this source leads 33 and 34 are connected to the switch mechanism and to the circuit or circuits to be energized thereby; lead 33 connects to brushes engaging slip rings 35, 36 and 37 associated with switch actuators 10, 11 and 12, 15 these slip rings being connected to contacts 21 on disk 19 which are connected in series as shown in Fig. 2. Lead 33 is also connected to terminals 38, 39 and 40 which represent one side of three circuits which may be energized by the switch mechanism. Slip ring 35 is connected to one end of the series of contacts 21 and the opposite end is connected to a slip ring 41 having a brush in contact therewith which in turn is connected to selector switch arm 32.

Lead 34 connects with brushes contacting slip rings 42 associated with each actuator and leads from these slip rings connect with each solenoid 17 in the respective actuator as well as with solenoid 28 for operating the cancellation plate 23. It will thus be seen that when selector switch arm 32 is positioned in engagement with one of the contacts 30 current will flow from lead 33, through slip ring 35 and the series of contacts 21 to switch arm 32, through the selected switch point 30, associated brush and slip ring to the corresponding solenoid 17, thus projecting the switch operating element or pin 15 outwardly of the actuator wheel 10. Upon movement of switch operator 15 wedge-shaped member 22 will be disengaged from contacts 21 thus opening the solenoid circuit and preventing energization of any other solenoid until the element 15 is returned to its inoperative position. The return circuit for the solenoid is of course through brush 42 and lead 34.

The circuits to be energized by the switch mechanism of this invention may be indicated by terminals 38 and 43, 39 and 44, and 40 and 45. Adjacent each actuator wheel 10, 11 and 12 there is disposed a switch having fixed contacts 46, 47 and 48 respectively and movable contacts 49, 50 and 51 respectively. Movable contact 49 is connected to the power source through lead 34 and fixed contact 46 is connected to terminal 43 of the first circuit and to movable contact 50 associated with switch actuator wheel 11. Fixed contact 47 is connected to terminal 44 associated with the second circuit and to movable contact 51 associated with switch actuator wheel 12. Fixed contact 48 is connected to terminal 45 associated with the third circuit.

In operation the three selector arms 32 will be moved to the desired position resulting in projection of the corresponding switch operating elements 15 to extended or operative position and for purposes of illustration this may be assumed to be element No. 2 in actuator 10, element No. 8 in actuator 11 and element No. 5 in actuator 12. The mechanism for rotating the actuators is then put in operation and if actuator 10 stops with element 15 corresponding to No. 2 in contact with movable switch contact 49, this circuit will be closed, thus energizing terminals 38 and 43 associated with the first circuit. This operation will likewise supply a source of current to movable

5 contact 50. If switch actuator wheel 11 stops with the switch operating element 15 corresponding with No. 8 in contact with movable switch contact 50, terminals 39 and 44 corresponding to the second circuit will be energized and a source of current will be supplied to movable contact 51. If switch actuating wheel 12 stops with switch operating element 15 corresponding to No. 5 in contact with movable contact 51 terminals 40 and 45 corresponding to the third circuit will be energized thus energizing all three circuits.

10 However, if only switch actuator 10 stops in the selected position the first circuit only will be energized since the switch associated with actuator 11 will not be closed and therefore neither the second circuit nor the third circuit will be energized. Likewise, if actuators 10 and 11 stop in selected position only the first two circuits will be energized since switch contacts 48 and 51 will remain open and the third circuit will likewise remain open.

15 Upon stopping of the switch actuating wheels 10, 11 and 12 it is necessary to recondition the mechanism for future operation and for this purpose the cancellation plate 23 must be actuated to return the extended switch operating elements 15 to retracted position thus reestablishing the circuit through contacts 21. This operation is accomplished by depressing cancellation button 52 which closes a circuit from power source lead 33 to slip rings 53 connected to each cancellation solenoid 28.

20 It will thus be seen that there has been provided by this invention a switch mechanism which may be utilized to select a series of conditions which if satisfied will result in the energization of one or more circuits and in which once made this selection cannot be changed. This mechanism is relatively simple and fool-proof and is also provided with a simple means for cancelling previous selections and returning the mechanism to original conditions for a subsequent operation.

25 It will be obvious to those skilled in the art that various changes may be made in the invention without departing from the spirit and scope thereof and therefore the invention is not limited by that which is shown in the drawings and described in the specification but only as indicated in the appended claims.

30 What is claimed is:

35 1. A permutation switch for energizing one or more circuits upon compliance with a series of selectively predetermined conditions comprising a switch associated with each circuit, means connecting said switches in series whereby the operation of each switch to energize its associated circuit is dependent upon the closing of the preceding switches, a rotatable switch actuator associated with each switch and having a plurality of selectively operable switch operating elements each comprising a member mounted in said actuator for movement to and from a retracted or extended position, drive means for rotating said 40 actuators, solenoid means operably associated with each operating element for moving the same to extended position, cancellation means on each actuator, means for operating said cancellation means to move extended operating elements to retracted position, selector switch means for selectively energizing said solenoids and means on said operating elements for rendering said selector switch means inoperative upon movement of one of said operating elements to operative 45 position.

2. A permutation switch for energizing one or more circuits upon compliance with a series of selectively predetermined conditions comprising a switch associated with each circuit, means connecting said switches in series whereby the operation of each switch to energize its associated circuit is dependent upon the closing of the preceding switches, a switch actuator associated with each switch and having a plurality of selectively operable switch operating elements each comprising a member mounted in said actuator for movement to and from a retracted or extended position, solenoid means operably associated with each operating element for moving the same to extended position, cancellation means on each actuator, means for operating said cancellation means to move extended operating elements to retracted position, selector switch means for selectively energizing said solenoids and means on said operating elements for rendering said selector switch means inoperative upon movement of one of said operating elements to operative position.

3. A permutation switch for energizing one or more circuits upon compliance with a series of selectively predetermined conditions comprising a switch associated with each circuit, a switch actuator associated with each switch and having a plurality of selectively operable switch operating elements each comprising a member mounted in said actuator for movement to and from a retracted or extended position, solenoid means operably associated with each operating element for moving the same to extended position, cancellation means on each actuator means for operating said cancellation means to move extended operating elements to retracted position, selector switch means for selectively energizing said solenoids and means on said operating elements for rendering said selector switch means inoperative upon movement of one of said operating elements to operative position.

4. A permutation switch for energizing one or more circuits upon compliance with a series of selectively predetermined conditions comprising a switch associated with each circuit, a switch actuator associated with each switch and having a plurality of selectively operable switch operating elements each comprising a member mounted in said actuator for movement to and from a retracted or extended position, means operably associated with each operating element for mov-

ing the same to extended position, cancellation means on each actuator means for operating said cancellation means to move extended operating elements to retracted position, selector means for selectively moving said operating elements and means on said operating elements for rendering said selector means inoperative upon movement of one of said operating elements to operative position.

5. A permutation switch for energizing one or more circuits upon compliance with a series of selectively predetermined conditions comprising a switch associated with each circuit, a switch actuator associated with each switch and having a plurality of selectively operable switch operating elements each comprising a member mounted in said actuator for movement to and from a retracted or extended position, means operably associated with each operating element for moving the same to extended position, cancellation means on each actuator, means for operating said cancellation means to move extended operating elements to retracted position and selector means for selectively moving said operating elements to operative position.

6. A permutation switch as defined in claim 2 in which said cancellation means comprises a disk, a series of apertures in said disk, said apertures slidably receiving said operating elements, a solenoid for moving said disk axially of said actuator and abutment means on said elements constructed and arranged for contact by said disk upon movement thereof to move extended elements to retracted position.

7. A permutation switch as defined in claim 2 in which said means for rendering said selector switch means inoperative comprises a disk of insulating material, a plurality of pairs of contacts on said disk one pair associated with each operating element, said contacts being connected in series and means on said operating elements for short circuiting said contacts when said elements are in inoperative position.
